(57) **CLAIM**

The ornamental design for a luminaire, as shown and described.

DESCRIPTION

FIG. 1 is a bottom perspective view of a luminaire showing our new design;

FIG. 2 is a bottom plan view thereof;

FIG. 3 is a left side elevational view thereof, the right side being a mirror image;

FIG. 4 is a top plan view thereof;

FIG. 5 is a rear elevational view thereof; and,

FIG. 6 is a front elevational view.

The characteristic feature of the design resides in the overall shape of the luminaire.

The broken line showing of square area light sources in FIGS. 1, 2 and 5 illustrate environmental structure and forms no part of the claimed design.
